United States Patent Office

Des. 229,047
Patented Nov. 6, 1973

229,047

HIGH CHAIR

Earl E. Lockwood, 35 Crosby St.,
East Hartford, Conn. 06118

Filed Jan. 15, 1971, Ser. No. 106,943

Term of patent 14 years

Int. Cl. D6—02

U.S. Cl. D15—1

FIG. 1

FIG. 2

FIG. 3

FIG. 4

FIG. 5

FIG. 6

FIG. 1 is a perspective view of the high chair showing my new design.

FIG. 2 is a front view thereof.

FIG. 3 is a top view thereof.

FIG. 4 is a bottom view thereof.

FIG. 5 is a rear view thereof.

FIG. 6 is a right-hand side view of the high chair, the left-hand side view being a mirror image thereof.

I claim:

The ornamental design for a high chair, as shown and described.
